Application May 29, 1930, Serial No. 457,301

6 Claims. (Cl. 123—179)

This invention relates to starter mechanism and more particularly to starters of the type employing as the motive force therefor a fluid under pressure.

5 One of the objects of the present invention is to provide a starter for internal combustion engines which is novel, simple and rugged in structure, and reliable in operation, so as to insure easy starting under all conditions without requiring the expenditure of much manual effort on the part of the operator.

Another object is to provide a novel engine starter which is characterized by the use of a fluid under pressure as the motive force which energizes the starter mechanism, and which is transmitted thereby to the engine to be started for cranking purposes.

20 Another object is to provide a novel starter for internal combustion engines in which the driving member of the starter mechanism is actuated by a fluid pressure engine.

25 Another object is to provide a novel engine starter which is entirely self-contained and independent of extraneous sources of power, thereby being especially well adapted for use with aircraft engines or other installations where the conservation of weight and space is an important factor.

30 Another object is to provide an engine starter of the fluid pressure type which embodies novel means for producing the fluid under pressure used as the motive force of the starter, said means being compactly attached to the starter structure and operating independently of the main engine or any other extraneous source of power.

35 A further object is to provide a starter for internal combustion engines embodying fluid pressure means for cranking the engine in which the fluid under pressure used as the motive force is produced by a novel automatic pistol mechanism.

40 A still further object is to provide an engine starter of the fluid pressure type embodying novel pistol means for producing the fluid under pressure, and also including means for manually actuating the starter mechanism independently of the pistol means.

45 These and other objects will appear more fully in the detailed description of the invention which follows. Although two embodiments of the present invention are described and illustrated in the accompanying drawings, it is to be expressly understood that these drawings are for the purposes of illustration only and are not to be construed as a limitation of the scope of the invention.

tion, reference being had for this purpose to the appended claims.

In the drawings:

Fig. 1 is a side elevation partly in section of one embodiment of the present invention;

Fig. 2 is a front elevation of the embodiment shown in Fig. 1 with a portion of the pistol mechanism in section;

Fig. 3 is a front elevation similar to Fig. 2 showing a second embodiment of the pistol mechanism;

Fig. 4 is a bottom end view of the cartridge magazine shown in Fig. 3; and

Fig. 5 is a side view of the magazine rotating means shown in Fig. 3.

Referring now to the drawings, wherein like reference characters indicate like parts throughout the several views, the embodiment of the present invention disclosed in Figs. 1 and 2 comprises a driving means adapted to be moved into engagement with and to crank a rotatable member of the engine to be started, a fluid pressure engine connected to said driving means for the purpose of rotating the same, and an automatic pistol mechanism which is adapted to fire a succession of explosive cartridges and thereby generate a fluid under pressure for supply to the fluid pressure engine. The driving means and the crank shaft of the fluid pressure engine are suitably housed and supported in a main casing member 6 which is detachably connected as by bolts 7 to a portion of the casing 8 of the engine to be started. Casing member 6 when viewed from the outer end as indicated in Fig. 2 is substantially circular in cross-section, but is provided with an internally threaded boss 9 extending outwardly from its substantially cylindrical surface, into which is threaded a cylinder 10 for the fluid pressure engine. The outer end of casing member 6 is open and an end plate 11 is secured thereto by any suitable means as shown which provides both a closure for said open end and a bearing for the fluid pressure crank shaft and the manual actuating means later to be described.

45 By thus providing the major portion of the starter casing in three parts, simplicity and ease of manufacture and assembly are insured, together with ruggedness of construction. Further, to facilitate assembly, inspection, and maintenance, a hand-hole 12 may be provided in the bottom of casing 6, a base plate 13 normally closing said opening and being detachably secured to casing 6 by any suitable means as by screws 14.

The fluid pressure engine which supplies the cranking torque to the engine to be started through the driving means later to be described, may be of any suitable construction, but as shown herein, comprises a single cylinder, reciprocating fluid pressure engine having a piston 15 housed within cylinder 10 and suitably secured as by a wrist pin 16 and a connecting rod 17 to a crank pin 18 which is formed as an integral part 5 of a crank shaft 19, the outer end of which is suitably journaled in a bearing sleeve 20 and boss 21 formed in end plate 11. Both crank pin 18 and crank shaft 19 are made hollow for the purpose of reducing weight, and economy of space 10 is also obtained by providing crank shaft 19 with a pair of circular flanges 22 and 23 integral with the ends of crank pin 18 for purposes later 15 to be described.

Suitable driving means are provided for transmitting the torque of crank shaft 19 to a rotatable member of the engine to be started for cranking purposes. In the form shown, a driving member 24, which is preferably in the form of a clutch jaw having inclined teeth and adapted to 20 engage a similarly formed clutch jaw 25 carried by a rotatable member of the engine to be started, such as the engine crank shaft or an extension thereof, is drivably connected to crank shaft 19 through suitable means including a 25 yieldable clutch. As shown in Fig. 1, a barrel member 26 is preferably formed integral with flange 23 of the crank shaft and is rotatably supported within casing member 6 adjacent engine casing 8, thus, in addition to its other functions, 30 forming the journal for the inner end of said crank shaft. Positioned centrally within driving barrel 26 is provided an interiorly threaded nut 27 which is drivably connected to said barrel member by means of a friction clutch comprising 35 a plurality of friction discs 28 which are splined alternately to the interior of barrel member 26 and the exterior of nut 27. Discs 28 are maintained in proper operative position between member 26 and nut 27 by means of an annular spacing member 29 interposed between the outermost friction disc and the inner face of flange 23, and by a second spacing member 30 placed 40 between the innermost friction disc and a shoulder 31 formed integrally with nut 27. Friction discs 28 are resiliently urged into frictional engagement with one another by means of a plurality of coil springs 32 which bear against a 45 thrust plate 33 adjacent shoulder 31 and which exert their thrust against an annular, exteriorly threaded nut 34 which is threaded into the interior of barrel member 26 and adapted to be locked in any desired position by suitable means such as a small locking plate 35 secured to nut 34 50 as by a screw 36 and projecting into one of a series of longitudinal slots 37 formed in the periphery of the outer end of barrel member 26. If desired, a ring 38 provided with studs 39 may be employed to maintain coil springs 32 in spaced 55 relation within the barrel member 26, and it will be understood that the pressure of said springs may be suitably adjusted by means of nut 34.

Any rotation of nut 27 received from driving barrel member 26 through the medium of the friction clutch will be transmitted to driving member 24 by means of an exteriorly threaded screw shaft 40 which is threaded within nut 27 and splined at its inner end to a hub 41 of driving member 24. A stop nut 42 is provided 60 on the outer end of screw shaft 40 in order to 65 limit the inward motion of said shaft by abutting

against a shoulder 43 formed interiorly of nut 27. Screw shaft 40 is provided with a hollow bore through which extends a rod 44 which is adapted to limit the movement of driving member 24 relative to screw shaft 40. For this purpose rod 44 is provided with an enlarged head 45 at its outer end which abuts the outer end of screw shaft 40, and at its inner end with a slotted nut 46 limiting the inward movement of driving member 24. A coil spring 47 is provided 70 adjacent the inner end of rod 44 for resiliently urging driving member 24 inwardly toward engine clutch jaw 25, said spring 47 being seated in a recess 48 formed in the inner end of screw shaft 40, surrounding rod 44 and exerting its 75 thrust against the inner face of driving member 24.

Driving member 24 is normally disengaged from engine member 25 and suitable means are therefore provided for advancing said driving member into cranking engagement with the engine member. As shown, said means are preferably constituted so as to be automatic in operation upon initial rotation of crank shaft 19 and the driving means, and comprise a plurality of longitudinally disposed slots 49 formed in the outer periphery of driving member 24 which are adapted to receive radial lugs 50 which project inwardly from the inner surface of a split ring 51 which is supported on the curved lip 52 of an oil-sealing member 53 which surrounds the inner end of the driving mechanism and is suitably secured between casing member 6 and engine casing 8. The three parts of split ring 51 are preferably retained in position on oil-sealing member 53 by means of a surrounding resilient member such as a coil spring 54. An oil-tight seal is formed around hub 41 of driving member 24 by means of a packing ring 55 of leather or other appropriate material which is suitably secured to member 53 as by means of a 80 plate 56 and rivets 57.

The structure thus far described constitutes, in general, the driving means which are adapted to engage and crank the engine to be started and the means for supplying the cranking energy to 85 said driving means which, as shown, is in the form of a fluid pressure engine. Any rotation of crank shaft 19 of the fluid pressure engine will be transmitted through barrel member 26, the friction clutch, nut 27, and screw shaft 40 to the 90 driving member 24. With the parts at rest, as shown in Fig. 1, any tendency to rotate driving member 24 will be resisted due to the slot and lug arrangement indicated at 49 and 50, and since screw shaft 40 cannot rotate independently of 95 driving member 24 due to their splined engagement, initial rotation of barrel member 26 and nut 27 will cause screw shaft 40 to move longitudinally to the right as viewed in Fig. 1, and, through the action of spring 47, will resiliently 100 urge driving member 24 into cranking engagement with engine member 25. When members 24 and 25 are fully engaged and screw shaft 40 has moved to its extreme outer position as determined by stop nut 42 and shoulder 43, the screw shaft 105 and driving member will take up the rotation of the remainder of the driving mechanism, split ring 51 then rotating on curved lip 52 of the oil-sealing member 53. When the engine to be 110 started starts under its own power and the speed of engine member 25 exceeds that of driving member 24, the latter will be pushed backwardly 115 out of engagement with member 25 due to the action of the inclined teeth, and screw shaft 40 will be retracted to its original position due to the 120

threaded engagement with nut 27, carrying with it, through the action of rod 44, the driving member 24. Should a backfire occur, the friction clutch will allow relative movement between nut 27 and the barrel member 26 and prevent any injury to the starter parts.

Referring now to the source of supply of the fluid under pressure which is used as the motive force for the fluid pressure engine, an automatic pistol mechanism has been provided which is adapted to fire a succession of explosive cartridges and thereby generate a fluid under high pressure, the timing of said explosions being synchronized with the operation of the fluid pressure engine by suitable means driven from the engine crank shaft, and the high pressure fluid thus produced being supplied to the cylinder of the fluid pressure engine by suitable means so as to act upon the piston of said engine. In the form shown in Figs. 1 and 2, a pistol barrel 58 is mounted in a vertical position adjacent cylinder 10 and supported by and secured to main casing 6 by any suitable means such as a pair of flanges 59 and 60 and a screw 61. A pipe or conduit 62 connects the upper end of pistol barrel 58 with cylinder 10 of the fluid pressure engine, and constitutes a cartridge explosion chamber for the pistol mechanism and a passageway for conducting the fluid produced by the explosion to the fluid pressure engine. The connection between pipe 62 and pistol barrel 58 may be made in any suitable manner as by means of a threaded nipple 63 formed on the end of pipe 62 and screwing into the interior of barrel 58, the connection being made gas-tight by means of a suitable gasket 64 interposed between the abutting surfaces of the two members. Suitable means are also provided for connecting the other end of pipe 62 to the cylinder 10 of the fluid pressure engine, which, as shown, comprise an externally threaded flange 65 formed on the end of pipe 62 which abuts a similar flange 66 formed as a part of a gland 67 which is threaded into the interior of a boss 68 formed integral with the top of cylinder 10, and a cup-shaped nut 69, the threads of which engage the threaded flange of pipe 62 while the inside of its head bears against flange 66 of gland 67. A suitable gasket is also provided between the abutting surfaces of flanges 65 and 66 in order to make the joint gas-tight.

A cylindrical cartridge magazine 71 is positioned alongside of pistol barrel 58 and is secured thereto by any suitable means as a bracket 72 on which the bottom of the magazine rests and a strap 73 encircling magazine 71 and pipe 62. The top of magazine 71 is provided with a removable cap 74 to facilitate the loading of the magazine with a plurality of explosive cartridges, and the lower portion of said magazine communicates directly with the interior of pistol barrel 58 through cooperating openings in the sides of said members so as to allow the transfer of cartridges from magazine 71 to the interior of pistol barrel 58, by suitable loading mechanism later to be described. It is to be understood that magazine 71 may be of any desired size so as to accommodate a sufficient number of cartridges for one or more starting operations.

Mounted within pistol barrel 58 so as to be longitudinally slidable therein, is provided suitable mechanism for performing the loading, firing, and ejecting operations of the pistol apparatus, which, in the form shown, comprises a bolt mechanism adapted for reciprocating movement within pistol barrel 58, a firing pin housed

within and capable of limited movement relative to said bolt mechanism, a cartridge positioning lever, and an extractor. The bolt mechanism comprises a piston-like breech plug 75 which is slidably mounted in and of substantially the same diameter as the bore of barrel 58, and a carrier 76 which is threaded to the exterior lower portion of breech plug 75 and which is slidably mounted within the lower enlarged portion of barrel 58. Carrier 76 is provided with a cam follower 77 suitably supported on a stub shaft 78 and adapted for engagement with a driving cam 79 which is secured to an extension 80 of crank shaft 19 by any desirable means such as a key 81 and lock nut 82. Carrier 76 is resiliently urged downwardly by a coil spring 83 interposed between a shoulder formed in barrel 58 and a similar shoulder formed in carrier 76 so as to maintain cam follower 77 in contact with cam 79 at all times. A reciprocating motion is thereby imparted to carrier 76 and the remainder of the bolt mechanism, which, by appropriate designing and setting of cam 79, will be synchronized with the operation of the fluid pressure engine.

A firing pin 84 having a striking point 85 is housed within breech plug 75 and normally occupies the position shown in Fig. 1 wherein a spring 86 surrounding firing pin 84 within a recess 87 formed in breech plug 75 exerts its thrust against a collar 88 formed on firing pin 84 and forces said firing pin to the upper limit of its travel relative to breech plug 75. In this position collar 88 bears against the upper end of recess 87 and striking point 85 of the firing pin projects slightly above the surface of a recessed seat 89 formed in the upper face of breech plug 75 and adapted to receive the base of an explosive cartridge. A gland 90 is threaded into the interior lower portion of breech plug 75 and acts both as a seat for spring 86 and a guide for a sleeve 91 which is threaded onto the lower portion of firing pin 84.

The position of firing pin 84 described in the preceding paragraph and shown in Fig. 1 is the position said pin would occupy after a cartridge had been fired. In order to fire a cartridge, however, it is necessary to cock the firing pin by withdrawing the striking point 85 below the surface of seat 89 and to retain it in said withdrawn position until the cartridge to be fired has been fully seated within the explosion chamber and the bolt mechanism has reached the limit of its upward travel. To perform this cocking and firing operation, suitable means are provided which comprise a trigger engaging finger or lug 92 which is formed integral with and projects laterally beyond the surface of sleeve 91 and extends through a longitudinal slot 93 formed in carrier 76. The outer end of lug 92 also extends within a longitudinal slot 94 formed in the lower portion of pistol barrel 58. This construction allows longitudinal movement of lug 92, sleeve 91 and firing pin 84 with the bolt mechanism relative to barrel member 58, and also allows a limited longitudinal movement of said parts relative to the bolt mechanism itself. Adjacent the upper limit of the longitudinal movement of carrier 76 there is provided a trigger member 95 pivotally supported on pistol barrel 58 as on a pin 96 which may be mounted in a bracket indicated at 97. Trigger 95 is provided at its upper end with a recess 98 within which there is seated a small coil spring 99 which bears against the surface of barrel 58 and urges this end of trigger 95 resiliently outwardly from said barrel. The lower end of

trigger 95 is provided with an inclined cam surface 100 and a tooth-shaped detent 101 which projects within longitudinal slot 94 formed in barrel 58. Detent 101 is adapted to engage the outer end of lug 92 as the bolt mechanism, including the firing pin, is moved upwardly by means of cam 79 from its lowermost position as shown in Fig. 1 (roller 77 being on the lowest point A of cam 79), and when such engagement occurs, firing pin 84 is held against further upward movement. Carrier 76 and breech plug 75, however, continue their upward movement and in so doing compress spring 86. This upward movement reaches its limit (indicated at point B on cam 79) when a trigger operating member 102 which is threaded into carrier 76 below and in line with slot 93, engages cam surface 100 of trigger 95 and rocks the latter around pin 96 against the tension of spring 99. Detent 101 is thereby withdrawn from lug 92 and the latter is released to allow firing pin 84 to be moved rapidly upward relative to breech plug 75 by the action of spring 86, causing striking point 85 to impinge against the bottom of a cartridge which has previously been positioned within seat 89 by mechanism later to be described, and causing an explosion.

Referring now to the cartridge positioning means, as shown in Fig. 2, a cartridge positioning lever 103 is pivotally supported in any suitable manner, as on a pin 104 supported in a bracket indicated at 105 formed integral with barrel 58, and its upper arm extends within the lower portion of cartridge magazine 71 through a slot 106 formed in the bottom and side of said magazine. The lower arm of lever 103 bears against a cam surface 107 formed integral with carrier 76 and projecting through a longitudinal slot 108 formed in the lower portion of barrel 58. In the position shown in Fig. 2, the bolt mechanism is at the lower limit of its longitudinal movement and is ready to begin the loading operation. The lower arm of cartridge positioning lever 103 is on the lowest point of cam surface 107 and the upper arm of said lever is in its extreme outer position which allows an unexploded cartridge 109 to drop to the bottom of magazine 71 ready to be moved to the right as viewed in Fig. 2 by the upper arm of cartridge positioning lever 103. As the bolt mechanism moves upwardly under the action of cam 79, the lower arm of lever 103 rides up on the face of cam surface 107 and the upper arm of said lever pushes the unexploded cartridge 109 to the right and positions the same on top of breech plug 75, so that continuing upward movement of the bolt mechanism will carry said cartridge within the bore of pipe 62 and seat it in its proper position for firing. At this time firing pin 84 will be withdrawn within the bolt mechanism so that striking point 85 is below the surface of seat 89, and the extractor rim 110 of cartridge 109 will be fully seated within said seat.

As the limit of upward movement of the bolt mechanism is reached, the firing pin is released as previously described and under the force of spring 86, striking point 85 is driven against the base of cartridge 109 causing an explosion, the fluid thus produced being conducted to the fluid pressure engine through the interior of pipe 62. The expansion of the fluid forces piston 15 of the fluid pressure engine downward thus rotating crank shaft 19 and the driving means. After about 120 degrees of the downward stroke of piston 15, an exhaust port 111 in the side of cylinder 10 is uncovered and allows the expanded fluid to

escape to the atmosphere. Cam 79 is so constructed, as shown in Fig. 2, that the bolt mechanism will be maintained at the limit of its upper travel from the time cartridge 109 is fired (indicated at C) until exhaust port 111 is opened (indicated at D), thus preventing any escape of the fluid under pressure through the pistol mechanism and thereby insuring that the maximum amount of energy obtainable from said fluid will be exerted upon piston 15.

As the bolt mechanism begins its downward movement, a spring extractor 112 which is secured within a longitudinal recess formed in the periphery of the upper end of breech plug 75 and which has a toothed head 113 normally resiliently urged to the left as viewed in Fig. 2, but having been forced to the right by inclined surface 63^a to allow cartridge 109 to be fully seated in recess 89 and in the explosion chamber, will clamp extracting rim 110 of the cartridge 109 and cause said cartridge to be withdrawn from the bore of pipe 62 and carried downwardly with the bolt mechanism. As the bolt mechanism approaches the lower limit of its longitudinal movement, the upper arm of lever 103 will begin to move to the left as viewed in Fig. 2 and to allow an unfired cartridge, which has previously been prevented from falling to the bottom of magazine 71 by means of the bent-over end 114 of said lever, to drop towards the bottom of said magazine ready for another load. When the bolt mechanism again begins its upward movement, the cycle previously described will be repeated and the unexploded cartridge in being moved to the right by lever 103 and positioned on top of breech plug 75 will eject the empty cartridge through a port 115 formed in the side of barrel 58.

Although the successive explosions produced by the pistol mechanism thus described are automatically regulated by means of cam 79 which is driven from crank shaft 19 of the fluid pressure engine, means must be provided for causing the initial explosion and for commencing the operations of the fluid pressure engine. Said means are preferably adapted for manual operation by the operator of the internal combustion engine which is to be started, and in the form shown comprise manual cranking means which are drivably connected to crank shaft 19 of the fluid pressure engine. A cranking shaft 116 is rotatably supported in a bearing sleeve 117 in a boss 118 formed in end plate 11 at right angles to the axis of crank shaft 19. The inner end of shaft 116 is provided with a bevel gear 119 secured thereto by any suitable means including a nut 120 and washer 121, which meshes with a large bevel gear 122 secured to flange 22 of crank shaft 19 in any suitable manner (not shown). The outer end of cranking shaft 116 is provided with a cylindrical crank head 123 which is secured thereto as by means of a shear pin 124 and provided with a cranking pin 125 having outwardly projecting ends 126 adapted to be engaged by an ordinary hand crank. Rotation of cranking shaft 116, which is in turn transmitted to crank shaft 19 of the fluid pressure engine, will not only actuate the pistol mechanism so as to cause an explosion and thereby operate the fluid pressure engine by the force thereof, but will also, through barrel 26 which is secured to crank shaft 19, impart rotation to the driving means and cause engagement of driving member 24 with engine member 25 by means of the automatic engaging mechanism previously described. By this means it is

possible to move driving member 24 into engagement with engine member 25 prior to the explosion produced by the pistol mechanism, and thus obtain the benefit of the full amount of energy created by the explosion for cranking purposes, none of it being expended in the preliminary step of causing cranking engagement of the members. It will also be understood that should the supply of explosive cartridges become exhausted, the starting operation may still be performed manually by the rotation of cranking shaft 116.

As previously described, and as shown in Fig. 2, end plate 11 is detachably secured to main casing member 6 by a plurality of screws. These screws are preferably provided at equally spaced intervals around the periphery of plate 11 so that said plate may be secured with cranking shaft 116 in any desired position as indicated by the dotted lines of Fig. 2, so as to facilitate cranking.

A second embodiment of the pistol mechanism is illustrated in Figs. 3, 4, and 5, and differs from the embodiment shown in Figs. 1 and 2 only in the construction of the cartridge magazine and loading means. As shown, a rotary magazine 126 provided with a plurality of cartridge recesses 127 is rotatably supported in a vertical position on a pin 128 between a pair of flanges 129 and 130, which may be formed integral with barrel 58, and extends within the barrel in such a manner that, as the magazine rotates, each of the cartridge recesses 127 may in succession be centered with respect to the bore of barrel 58 and the bolt mechanism. Each recess 127 is provided at its lower end with a plurality of projections 131, preferably three in number, which are integral with magazine 126 and extend radially inwardly from the periphery of the recess to form a seat for the bottom of an explosive cartridge 132.

After a cartridge has been positioned concentrically with the bore of barrel 58 by the magazine rotating means later to be described, the bolt mechanism is adapted to move upwardly through recess 127 and to advance cartridge 132 to its proper firing position within the explosion chamber of pipe 62. For this purpose breech plug 75 is provided in its periphery with a plurality of longitudinal grooves 133 which correspond to and are adapted to receive projections 131 during the upward travel of the bolt mechanism. When cartridge 132 is fully seated, it is fired in a manner similar to that previously described in connection with Figs. 1 and 2.

The extracting means for withdrawing the empty cartridge case 132 from pipe 62 after the explosion comprises a spring extractor 134, similar to extractor 112, secured by any suitable means to the outer surface of breech plug 75 in the same vertical plane with pin 128 and provided with a toothed head 135. The normal tension of spring extractor 134 maintains head 135 in the position shown in Fig. 3, away from the top of breech plug 75, as long as it moves within a longitudinal groove 136 formed in the inner wall of barrel 58, the upper end of which extends above the lower portion of magazine 126. This construction allows the bolt mechanism to move upwardly and engage the bottom of cartridge 132 before the extractor is resiliently urged inwardly by the cam-like construction of the upper end of groove 136 so as to cause toothed head 135 to project within a longitudinal peripheral groove 137 formed in the magazine 126 and communicating with recess 127, and to engage the extracting rim 110 of the cartridge. After the

cartridge has been fired, this toothed engagement of head 135 with rim 110 will withdraw or extract the empty cartridge case from the explosion chamber and return it to recess 127 within magazine 126, the toothed engagement being released by the spring action of extractor 134 when groove 136 is reached in the downward travel of the bolt mechanism.

Suitable means must also be provided for automatically rotating magazine 126 after each cartridge is fired in order to present a fresh one for the next load, which, as shown, may comprise a magazine operating lever 138 secured at its lower end to a hub 139 which is pivotally mounted on a pin 140 supported in a pair of brackets indicated at 141 as projecting from the surface of barrel 58, and having at its upper end a pivotally mounted finger 142 which is adapted to engage one of a plurality of lugs 143 circularly arranged on the bottom of magazine 126. Hub 139 is also provided with a short arm or cam follower 139a, similar to the lower arm of lever 103 shown in Fig. 2, which bears against cam 107 of carrier 76 and acts in a manner similar to that previously described in connection with lever 103 to rock lever 138 about its pivot and, due to the engagement of finger 142 with lugs 143, to rotate magazine 126 so as to successively bring the various recesses 127 in line with the bore of the pistol mechanism. Finger 142 is pivoted as on a pin 144 and is provided with a suitable spring 145 so as to maintain its normal position as shown in Fig. 3 when rotating the magazine, and yet to allow it to resiliently yield when passing over the next lug on the return movement of lever 138.

Each recess 127 is accurately centered with the bore of the pistol mechanism, and magazine 126 is held against further rotation after being thus centered, by means of a detent 146 which is housed in and projects from the bottom of upper flange 129, and is resiliently urged into engagement with one of a plurality of depressions 147 suitably formed and located in the upper end of magazine 126, by means of a small spring 148 which is compressed within the recess housing detent 146 by a suitable screw 149.

With this type of magazine, in order to load a fresh supply of explosive cartridges, it is only necessary to withdraw pin 128 and remove magazine 126, either replacing it with a full one or reloading and replacing the one removed by dropping a cartridge into each recess 127 from the top, projections 131 forming a seat therefor and preventing the cartridge from dropping through the magazine.

Describing now the operation of the present invention, the operator of the internal combustion engine to be started first loads the cartridge magazine with a plurality of unexploded cartridges so as to provide sufficient ammunition to produce a sufficient number of successive explosions to insure a successful start. An ordinary hand crank is then fitted to the end of cranking shaft 116 and is rotated slowly until driving member 24 has been fully engaged with engine member 25 due to the rotation of driving barrel 26 and the cooperation of the rest of the driving mechanism as previously described. At the same time, this initial rotation of cranking shaft 116 has caused rotation of cam 79 and through roller 77 has moved the bolt mechanism of the pistol means upward from its lowermost position (indicated at A in Fig. 2), thus starting to move a cartridge upward toward its firing position within the lower portion of explosion 75

- chamber of pipe 62. As cranking shaft 116 continues to be rotated, the bolt mechanism will be further advanced upwardly towards firing position, and, at point B on cam 79, lug 92 engages 5 detent 101 of the trigger mechanism and the cocking operation is started. Still further rotation advances the bolt mechanism until point 10 C on the cam is reached when trigger operating member 102 forces detent 101 outwardly so as to release lug 92 and allow the firing pin to be rapidly forced upwardly against the base of the cartridge which is now securely seated within the explosion chamber. As previously described, 15 cam 79 is so formed that when the explosion takes place, piston 15 is at the top of its stroke. The fluid which is produced as a result of the explosion of the cartridge is under very high pressure and is conveyed through pipe 62 to the interior of cylinder 10 and there acts upon piston 20 15 so as to force it rapidly downward, said movement being transmitted to crank shaft 19 and through driving barrel 26 and the remainder of the driving means to the engine member 25, thus cranking the engine to be started. 25 The hand crank attached to cranking shaft 116 will be automatically disengaged upon the first explosion due to the usual pin and slot connection, and subsequent explosions will be produced automatically by the rotation of crank 30 shaft 19 under the action of the fluid pressure engine. The engine to be started will thus be continuously cranked until it starts under its own power at which time members 24 and 25 are 35 disengaged due to the action of the inclined teeth, driving member 24 being fully withdrawn to its original position when the fluid pressure engine ceases to operate. It will be understood that, if desired, the cartridges may be loaded 40 and fired singly, particularly in those installations where experience proves that one explosion is sufficient to start the main engine. Should a backfire occur during the starting operation, the friction clutch will allow relative motion between nut 27 and driving barrel 26 and thus 45 protect the starter parts from injury. Should, for any reason, a supply of unexploded cartridges be unavailable, the starting operation may be performed manually as previously described by rotating the hand crank attached to cranking 50 shaft 116. There is thus provided a starter for internal combustion engines which is simple and rugged in structure, efficient and reliable in operation, and easily attachable to any internal combustion 55 engine. It is especially well adapted for use with aircraft engines because of its compactness, lightness, and independence of electric batteries or compressed fluid storage tanks or other accessories which are usually required for starting installations for engines of this type. The present structure is entirely self-contained and normally derives its motive power by the explosion of a cartridge, although, if necessary, the mechanism may also be actuated by manual means. 60 The present invention provides a driving member which is adapted to engage and crank a member of the engine to be started, combined with a fluid pressure engine and manual means for rotating said driving member. The engagement of the driving member with the engine member is performed automatically upon rotation of the driving means, and means are provided for causing said engagement prior to the actuation of the fluid pressure engine so as to 65 derive the greatest benefit possible out of the 70 75

fluid produced for actuating said engine. Finally, a novel automatic pistol mechanism has been provided for producing the fluid under pressure which operates the fluid pressure engine, which means are automatically driven and synchronized with the operation of the fluid pressure engine. 5

It will be obvious that the invention is not limited to the specific forms described and illustrated in the drawings, but is capable of a variety of mechanical embodiments. For example, any suitable fluid pressure engine such as a multi-cylinder radial engine might be substituted for the one shown in the present embodiment, or the pistol mechanism provided might be replaced by any equally suitable device. Various other changes, which will now appear to those skilled in the art, may be made in the form, details of construction, and arrangement of the parts without departing from the spirit of the invention, and reference is therefore to be had to the appended claims for a definition of the limits of the invention. For claims to features shown but not claimed herein, reference is to be had to my application No. 24,910 filed 25 June 4, 1935.

What is claimed is:

1. In a starter for internal combustion engines, the combination of a fluid pressure engine having a driving shaft, a barrel member formed integral with said driving shaft, an engine engaging member, means for operatively connecting said barrel member to said engine engaging member, pistol means for producing a fluid under pressure for supply to said fluid pressure engine, and means driven by said driving shaft for automatically actuating said pistol means.

actuating said pistol means.

2. In a starter for internal combustion engines, the combination of an engine engaging member, a fluid pressure engine having a drive shaft co-⁴⁰axial with said engine engaging member, a barrel member secured to said driving shaft for rotation therewith, means for yieldingly connecting said barrel member and said driving member, pistol means for producing a series of explosions thereby generating a fluid under pressure for supply to said fluid pressure engine, and means driven by said driving shaft for automatically actuating said pistol means.

3. In a starter for internal combustion engines, 50
the combination of an engine engaging member,
a fluid pressure engine having a drive shaft co-
axial with and drivably connected to said driving
means so as to transmit rotation thereto, means 55
effective upon initial rotation of said driving
means for automatically shifting said engine en-
gaging member to engine engaging position,
pistol means for producing a fluid under pressure
for actuating said fluid pressure engine, and man-
ually rotatable means for causing operation of 60
said shifting means and by the same action mov-
ing said pistol means into pressure generating
position.

4. An engine starter comprising in combination, an engine engaging member, a fluid pressure engine having a drive shaft coaxial with said engine engaging member, means for drivably connecting said drive shaft and engine engaging member to rotate the latter said connecting means including a barrel member and a second part effective upon initial rotation of said barrel member to automatically advance said engine engaging member into cranking engagement, pistol means for producing a series of explosions thereby generating a fluid under pressure for supply to 75

5 said engine, means driven by said engine for automatically actuating said pistol means in synchronism with the operation of said engine, and manually rotatable means for causing said engine engaging member to move into engagement with the engine member and by the same action moving said pistol means into explosion producing position.

10 5. In apparatus of the class described, the combination with an engine engaging member, of a fluid pressure engine having a driving shaft coaxial with said engine engaging member and a barrel member integral with said driving shaft and surrounding a portion of said engine engaging member, means for drivably connecting said barrel member and said engine engaging member, a pistol mechanism adapted to fire a succession of explosive cartridges thereby generating a fluid 15 under pressure, means for supplying said fluid to said fluid pressure engine, means including a cam secured to said driving shaft for automatically actuating said pistol mechanism in synchronism with the operation of said fluid pressure engine, 20 means effective upon manual rotation of said driving shaft for causing said engine engaging member to move to engine engaging position and by the same action moving said pistol mechanism to explosion producing position.

6. In apparatus of the class described the combination with an engine engaging member, of a fluid pressure engine having a driving shaft coaxial with said engine engaging member, a barrel member integral with said driving shaft and surrounding a portion of said engine engaging member, means for drivably connecting said barrel member and said engine engaging member, a pistol mechanism adapted to fire a succession of explosive cartridges thereby generating a fluid 10 under pressure, means for supplying said fluid to said fluid pressure engine, means including a cam secured to said driving shaft for automatically actuating said pistol mechanism in synchronism with the operation of said fluid pressure engine, 15 means effective upon manual rotation of said driving shaft for causing said engine engaging member to move to engine engaging position and by the same action moving said pistol mechanism 20 to explosion producing position.

ROMEON M. NARDONE.
